US00D644904S

(12) **United States Design Patent**
Saunders

(10) **Patent No.:** **US D644,904 S**
(45) **Date of Patent:** **** Sep. 13, 2011**

(54) **SKEW RABBET BLOCK PLANE**

(75) Inventor: **Terry R. Saunders**, North Gower (CA)

(73) Assignee: **Lee Valley Tools, Ltd.**, Ottawa, Ontario (CA)

(**) Term: **14 Years**

(21) Appl. No.: **29/357,758**

(22) Filed: **Mar. 17, 2010**

(30) **Foreign Application Priority Data**

Oct. 22, 2009 (CA) 132614

(51) **LOC (9) Cl.** **08-03**

(52) **U.S. Cl.** **D8/101**

(58) **Field of Classification Search** D8/14,

D8/51, 98, 101; 30/484, 487-488, 490-491

See application file for complete search history.

(57) **CLAIM**

The ornamental design for skew rabbet block plane, as shown and described.

DESCRIPTION

FIG. 1 is a perspective view of the skew rabbet block plane of this invention.

FIG. 2 is another perspective view of the design for the skew rabbet block plane shown in FIG. 1.

FIG. 3 is a left side elevation view of the design for the skew rabbet block plane shown in FIG. 1.

FIG. 4 is a front end view of the design for the skew rabbet block plane shown in FIG. 1.

FIG. 5 is a right side elevation view the design for the skew rabbet block plane shown in FIG. 1.

FIG. 6 is another end view of the design for the skew rabbet block plane shown in FIG. 1; and,

FIG. 7 is a top plan view of the design for the skew rabbet block plane shown in FIG. 1.
